UNITED STATES PATENT OFFICE.

ALPHONS KREMER, OF GULFPORT, MISSISSIPPI.

VALVE.

1,033,326.

Specification of Letters Patent.

Patented July 23, 1912.

Application filed October 20, 1910. Serial No. 588,074.

To all whom it may concern:

Be it known that I, ALPHONS KREMER, a citizen of the United States, residing at Gulfport, in the county of Harrison and State of Mississippi, have invented certain new and useful Improvements in Valves, of which the following is a specification.

This invention relates to valves, and more particularly to what is known as globe valves, and may be applied to all of the various forms of valves manufactured, and to valves employed for various purposes, and has for one of its objects to provide a simply constructed device wherein yieldable packings are dispensed with, and the pressure of the steam or water utilized to maintain the valve in steam or water tight condition.

Another object of the invention is to provide a device of this character wherein the movable portions of the valve are arranged steam tight within the casing and without exposing any of the fragile portions of the structure to the direct action of the steam or water.

With these and other objects in view, the invention consists in certain novel features of construction hereinafter shown and described and then specifically pointed out in the claim and in the drawing illustrative of the preferred embodiment of the invention.

Figure 1 is a sectional elevation of the improved valve. Fig. 2 is a transverse section on the line 2—2 of Fig. 1. Fig. 3 is a side elevation partly in section, illustrating a modification in the construction.

The improved device comprises a body 10 having means at one end, at 11, for connecting the intake and with means at the opposite ends, at 12, for connecting the discharge. The casing 10 is of the ordinary construction and provided with an internal valve seat 13 and an internally threaded opening, represented at 14, above the valve seat. Engaging the threaded opening 14 is a hollow cap or casing 15 having a longitudinal bore 16 at the upper end and with an annular shoulder 17 adjacent to the bore. The casing 15 is formed with its inner sides extending in parallel relations, and slidably disposed within the casing and closely engaging the same is a relatively elongated sleeve 18 having a valve face 19 at the lower end for engaging the valve seat 13 of the body. The member 18 is internally threaded, and fitting within this threaded portion is a relatively large threaded plug 20, the

plug being provided at its upper end with an annular rib 21 for engaging the shoulder 17. The plug 20 is provided with a stem 22 extending beyond the upper end of the cap 15 and provided at its upper end with a suitable hand wheel 23. The hub portion of the hand wheel is provided with a depending annular sleeve 24 which bears around the stem 22 of the plug and spaced a considerable distance therefrom, thus leaving ample space for the reception of a relatively heavy spring 25, the spring being arranged to bear upon an annular wear member 27, preferably of vulcanite or similar material, so that the cap is relieved largely from the strain otherwise imparted to it when the binding nut 28 of the hand wheel 23 is applied. By this arrangement it will be obvious that the rib 21 is retained in steam and water tight engagement with the annular shoulder 17, so that when the hand wheel 23 is rotated, and corresponding motion imparted to the plug 20, the valve sleeve 18 will be operated without permitting any steam or water to escape. By this means a packingless valve is produced which is capable of withstanding any pressure without leaking. The cap 15 is provided with dovetailed ribs 29, while the member 18 is provided with correspondingly dovetailed channels 30, so that the member 18 is movable longitudinally thereof within the cap, but is prevented from rotation therein. By this simple means the plug 20, it will be noted, may be rotated to cause a longitudinal movement to the member 18 and thus open and close the main valve, while at the same time rotary motion of the plug is produced without danger of leakage around the stem 22.

In Fig. 3 is shown a view of the valve showing a modification in the construction, the modification consisting in substituting pins 31, preferably of steel, for the dovetailed ribs 29, which perform the same function as the ribs, and may be employed as substitutes therefor under certain conditions if required, but this slight change does not constitute a departure from the principle of the invention, as the operation is the same as when the ribs are employed.

Having thus described my invention, what is claimed as new is:

In combination with a valve body having a valve seat, a hollow cap having at its upper portion a seat and provided at its upper end with a flat surface, a stem journaled

in the cap and having an annular rib adapted to fit against said seat in the cap, a wheel fixed to the upper end of the stem and having at its hub a tubular sleeve, an annular plate interposed between the lower end of the tubular sleeve and the flat top of the cap, a coiled spring housed within the sleeve and exerting pressure against the wheel to hold said annular rib in engagement with the seat of the cap, a screw plug depending from

the stem, and a valve slidably mounted in the cap and restrained against rotation and engaged by said screw plug.

In testimony whereof, I affix my signature in presence of two witnesses.

ALPHONS KREMER. [L. s.]
